UNITED STATES PATENT OFFICE.

I. J. FEARING, OF SOUTH WEYMOUTH, MASSACHUSETTS.

BUTTONHOLE-CUTTER.

Specification of Letters Patent No. 32,281, dated May 14, 1861.

To all whom it may concern:

Be it known that I, I. J. FEARING, of South Weymouth, in the county of Norfolk and State of Massachusetts, have invented a new and useful Attachment for Scissors, the Same being for Cutting Button-holes in Garments; and I do hereby declare that the following is a full, clear, and exact description of the same, reference being had 5 to the annexed drawings, making a part of this specification, in which—

Figure 1, is a side view of my invention applied to a pair of scissors. Fig. 2, a section of the scissors, taken in the line x, x , 10 Fig. 1.

Similar letters of reference indicate corresponding parts in the two figures.

The object of this invention is to obtain a simple and efficient cutting device that may 20 be very readily applied to a pair of scissors for the purpose of cutting button holes; the device when not required for use admitting of being readily detached from the scissors so that the latter may be used for their legitimate purpose.

The invention consists in the employment or use of a cutting blade provided with a "shear" edge and a point and applied to one of the blades of the scissors so as to effect 30 the desired end.

To enable those skilled in the art to fully understand and construct my invention I will proceed to describe it.

A, represents a cutter constructed of steel 35 and which may be described as being formed of a plate of taper or wedge shape bent over at its smaller end to form a loop or eye a , as shown clearly in Fig. 2, by which the cutter may be fitted to one of the blades 40 b , of the scissors.

The cutting edge of this cutter is at the widest end of the plate and it is formed of a shear or beveled edge c , and a point d , the latter being at the inner part of the cutter as shown clearly in Fig. 1, and the 45 beveled part c , inclining slightly upward. The cutter should be so adjusted to the blade b that it will work snugly over the cutting edge of the other blade e , of the scissors. The small end f , of the cutter 50 plate serves as a stop for the blade e , and prevents the blade of the scissors coming in contact at their outer parts and cutting the fabric.

From the above description it will be seen 55 that when the cutter A, is applied to the blade b , a slit may be cut through the cloth equal to the length of the cutter A, and the length of the blade of course should correspond to the desired length of the button 60 hole. Cutters therefore of different sizes may be used according to the size of the button holes required. The point d , of the cutter A punctures the cloth previous to the cut and greatly facilitates the operation. 65

I do not confine myself to the means herein shown and described for securing the cutter to the scissors, for various plans may be devised for that purpose; but

I do claim as new and desire to secure by 70 Letters Patent,

A supplemental cutting blade A, constructed substantially as described and applied to a pair of scissors to operate substantially as and for the purpose herein set 75 forth.

ISRAEL J. FEARING.
